UNITED STATES PATENT OFFICE.

MORRIS S. WRIGHT, OF WORCESTER, MASSACHUSETTS, ASSIGNOR TO MORRIS S. WRIGHT COMPANY, OF WORCESTER, MASSACHUSETTS, A CORPORATION OF MASSACHUSETTS.

EXHAUST APPARATUS.

1,089,178.

Specification of Letters Patent.

Patented Mar. 3, 1914.

Application filed September 1, 1910. Serial No. 580,138.

To all whom it may concern:

Be it known that I, MORRIS S. WRIGHT, a citizen of the United States, residing at Worcester, in the county of Worcester and 5 State of Massachusetts, have invented certain new and useful Improvements in Exhaust Apparatus, of which the following is a specification, reference being had therein to the accompanying drawing.

10 This invention relates to an exhaust apparatus and though susceptible of a variety of adaptations it is designed primarily for use in connection with pneumatic cleaning systems, wherein is employed a nozzle or the 15 like adapted to play over a surface to be cleaned, the apparatus operating to draw into the machine the dust laden air and to exhaust the air therefrom.

More particularly, the invention includes 20 a plurality of pumps, conveniently power actuated, with novel means for supporting the same upon a suitable wind chest, vacuum chamber or the like.

Further, the invention comprises novel 25 instrumentalities whereby the pumps may be separately removed as independent and complete units, permitting each pump to be replaced at will without interfering with the associated pumps or other parts of the apparatus, and to afford ready access to the 30 valve mechanism of the vacuum chamber or the like which is in communication with the pumps.

The invention also includes improved 35 power actuating means for the pump and supporting mechanism for the latter.

Again the invention embraces a novel 40 form of vacuum chamber or wind chest with simple and effective means for guarding the valve mechanism thereof from the dust, and preventing the passage of the dust into the pumps from said chamber.

Other improvements, including novel details in the construction and arrangement of 45 the parts, thereby forming a simple, practical, more efficient and inexpensive mechanism for the purpose stated, will be more particularly brought out in the following specification, which for a clear and complete 50 understanding of the invention should be considered in connection with the accompanying drawings forming a part hereof, and wherein is disclosed, for the purpose of illustration, a convenient and satisfactory 55 embodiment of the invention.

In the drawings: Figure 1 is a side view in elevation, the parts being shown in section for the purpose of illustration. Fig. 2 is a top plan view. Fig. 3 is an end elevation. Fig. 4 is a detail perspective view of a removed part of the apparatus enlarged.

Referring now more particularly to the drawings wherein like reference numerals refer to similar parts throughout the several views, 1 is the base of a wind chest, vacuum chamber or the like, the latter also having sides 2 a rear end 3 and a top 4, the said top resting upon the upper surface of the sides 2 and end 3 and secured to the latter in any suitable manner. A removable front 5 is 60 provided for the front end of the vacuum chamber, the same overlying the top, bottom and side walls just referred to, and a suitable packing 6 being interposed between the ends of said walls and the removable front 5, the packing being conveniently secured to the removable front 5. Also secured to the removable front wall 5 is a drawer 7 in which latter may be mounted a suitable filtering bag 8. The removable front wall 5 has an opening 9 therein adapted to register with the open end of the bag 8 and in which said opening is adapted to be mounted a tube or the like 10 for connection with a suitable nozzle or the like adapted to 70 play over a surface to be cleansed.

Positioned upon the top 4 of the vacuum chamber 1 are a plurality of pumps, the same being conveniently arranged in pairs and there being a pair adjacent each end of 75 the wind chest. Each of these pumps together with the supporting mechanism therefor are substantially the same in each instance, and a description of one will suffice for the others. The pumps comprise an inner relatively fixed section 11, a movable section 12 hinged to the relatively fixed section 11 in any desired manner as at 13, the 80

said sections being connected by the usual diaphragm 14. The fixed section of the pumps has an opening intermediate its ends shown at 15 for the admission of air and the movable section has an opening or plurality of openings 16 for the exhaust, the said opening 16 being normally closed by a flap valve member 17 secured at its upper end to the outer surface of the member 12 and spring held as at 18 at its lower end to said member 12. The flap valve member 17 is conveniently 85 of very flexible material, the same being re- 100

105 110

inforced as by substantially non-yielding disks 19, the latter being positioned on the valve member 17 one adjacent each of the openings 16. Elongated metallic brackets 5 or supports 20 are provided for the pumps, the same being preferably inclined upwardly and inwardly and secured to the outer face of the fixed section 11 as by removable screws 21. The said bracket members 20 connect with and conveniently are made integral with the tubular conduits 22 which later terminate in offset feet 23 resting upon the top 4 of the vacuum chamber, and secured to the latter as by removable screws 23'. The conduits 22 establish a vertical passage way 24 and one wall thereof is cut away at 25, thereby forming a transverse opening connecting with the opening 15 in the fixed member 11 of the pump. The top 4 of the 10 vacuum chamber is provided with openings 26 one for each conduit 22, and arranged to normally close said openings 26 is a disk valve 27 one for each opening, said valve adapted to rest on the outer surface of the top 15 wall 4 and having a projecting stem 28 slideable in an aperture of a valve bracket 29 also positioned on the top 4 of the vacuum chamber. The disk-shaped valves 27 have a suitable reinforcing backing 30 adapted 20 to contact with the top of the bracket 29 to limit the opening movement thereof.

Positioned upon the top 4 of the vacuum chamber is a suitable motor 31, the same being conveniently arranged intermediate 25 the ends of the vacuum chamber between the pumps at the ends thereof, the said motor having projecting from one side thereof a drive shaft 32 extending transversely of the vacuum chamber and having mounted thereon 30 for movement therewith a drive pinion 33 which latter is arranged to mesh with a gear wheel 34 mounted upon what may be termed the pump drive shaft 35 which latter extends across the machine and is suitably 35 supported adjacent opposite ends in bearings 36 mounted upon longitudinally extended supports 37. The said supports 37 rest at their opposite ends upon offset flanges 38 adjacent the upper ends of the brackets 40, and being secured in position by removable bolts 39 passing through the sides of the brackets 20 and the ends of the supports 37 as more clearly shown in Fig. 1. The 45 pump drive shaft 35 is in the nature of a 50 crank shaft having crank members 40 and 40' projecting respectively in different directions and connected to said cranks are suitable pitman rods 41 one for each movable section of the pumps, the construction 55 being such that a pump at one end of the machine is in substantial alignment with a pump at the opposite end of the machine, and the rod 41 for the movable section of one of said pumps is bifurcated at its end 60 to form a yoke for the reception of the ter-

70 minal of the other rod, said terminal and bifurcated portion being sleeved upon the crank as clearly illustrated in Fig. 2. The movable sections of the pumps have fastened thereon a bracket member which overlies 75 the outer surface thereof and constitutes a reinforcement therefor the said bracket members being designated by the numeral 42 and having a flange 42' overlying the upper edge of the movable section 12, and also 80 having an upwardly extended portion 43 constituting a bearing 44 for the outer ends of the rods 41. It will be noted that the bracket 42 with the extension 43, which is conveniently formed of metal constitutes a 85 very substantial support for the operating pitman rods, and position the same above the upper end of the metallic supporting brackets 20 and longitudinally extending supports 37, permitting free back and forth 90 movement of the movable sections 12.

From the description thus far and from an inspection of Figs. 1 and 2 of the drawings, it will be observed that in operation, movement being imparted to the pitman 95 rods through the medium of the motor and the parts connected to the drive shaft 35, as the movable sections 12 of the pumps move outwardly about their hinged connection 13, the flap valves 17 will be held closed, while 95 the disk valve 27 will be automatically raised by the suction created thereby drawing the dust laden air through the connection 10 into the filtering bag 8 and the substantially cleansed air through the opening 105 26 into the closed passage way 24 and thence into the pump through the opening 15. As the movable section of the pump is given a reverse movement, that is inwardly, the valve 27 will automatically seat thereby 105 shutting off the communication between the vacuum chamber and the conduit 22, and the flap valve 17 will be opened, thereby permitting the air to exhaust from the pump through the openings 16. The pumps are 110 so positioned and the drive connections for the movable sections so arranged that as the movable section of one pump at one end of the machine is moved in one direction the movable section of the coöperating pump 115 at the opposite end of the machine will move in a reverse direction, and the movable section of a succeeding pump at one end of the machine will move in a reverse direction to the movable section of the adjacent pump 120 at the same end of the machine. The result is that a continuous suction is maintained in the vacuum chamber, and this suction will be very powerful. The brackets 20 not only constitute a very firm and substantial reinforcement for the fixed section 11 of the connected pump but as well a substantial support for the longitudinally supporting members 37, and also a closed conduit 125 for the passage of the air from the 130

vacuum chamber to the pumps. Again the inclosed conduit 22 constitutes a protecting medium for the movable valves 27 and affords a direct passage way for the air from the opening 26 of the vacuum chamber to the opening 15 of the pump. It will also be appreciated that the pumps themselves are free from connection with the vacuum chamber, and are supported through the medium of the metallic bracket members 20 with the result that by removing the securing means 23' and the securing means 39, the said brackets with the connected pump may be bodily removed as an independent unit for access either to the pumps or to the valves 27. This constitutes an important feature of the invention, and even should one of the pumps be removed the supporting members 37 and the parts mounted thereon will be supported and retained in position by the remaining brackets 20.

Means in addition to the filtering bag 8 is provided for further protecting the openings 26, valves 27, etc., from the dust which may leak with the air through the filtering bag 8, the said means including a diaphragm 45, preferably of cloth, the said diaphragm being secured to a rectangular frame 46 by an overlapping frame 47 and retaining screws 48. The diaphragm with its connected frame is slidably mounted upon supporting guides or runways 49 secured to the walls of the vacuum chamber, and it will be noted that the diaphragm may be moved from the open end of the machine by sliding the same along the runway 49, after removing the front wall 5, as previously described. Since the diaphragm extends substantially from end to end and side to side of the vacuum chamber, the other parts of the machine will be protected from the admission of dust, etc., and the detachable characteristic of this diaphragm makes it possible to readily cleanse the same, or to replace as occasion demands.

What I claim is:

1. In an apparatus of the character described, a vacuum chamber having an outlet in its top adjacent opposite ends, a motor supported on the top of the vacuum chamber intermediate said outlets, a drive wheel having operative connection with said motor, a shaft for the wheel, pumps adapted to have communication with said outlets, one member of each pump being stationary, and the other movable, a longitudinally extending support for said shaft extending between and supported upon the stationary members of the pumps, and connections between said drive wheel and the movable members of the pumps for operating the latter.

2. In an apparatus of the character described, a vacuum chamber having an outlet in its top adjacent opposite ends, a motor supported on the top of the vacuum chamber

intermediate said outlets, a drive wheel having operative connection with said motor, a shaft for the wheel, pumps adapted to have communication with said outlets, one member of each pump being stationary, and the other movable, a longitudinally extending support for said shaft extending between and supported upon the stationary members of the pumps, and connections between said drive wheel and the movable members of the pumps for operating the movable members of the respective pumps alternately in opposite directions.

3. In an apparatus of the character described, a vacuum chamber having in its top adjacent opposite ends an outlet opening, pumps one adjacent opposite ends of the vacuum chamber, said pumps comprising a fixed and a pivotally connected member, the fixed member having communication with the adjacent outlet of the vacuum chamber, a longitudinally extending support projecting between and supported on the fixed members of the pumps, a transversely extending drive shaft having a bearing in said longitudinally extending support and opposite rods connecting at one end with a movable member of the pumps, and at their oppositely disposed ends with said shaft.

4. In an apparatus of the character described, a vacuum chamber having two outlets, a pump for each outlet, said pumps each comprising a relatively fixed and a movable member, means for supporting the fixed members on the vacuum chamber, a motor also supported on the vacuum chamber between the ends thereof, a gear projecting therefrom, a drive wheel having a gear connection with the motor gear, a crank shaft for said drive wheel and oppositely extending arms connected to said shaft for movement by the latter, said arms having connection respectively with the movable members of the pumps.

5. In an apparatus of the character described, a vacuum chamber having two outlets, a pump for each outlet, said pumps each comprising a relatively fixed and a movable member, means for supporting the fixed members on the vacuum chamber, a motor also supported on the vacuum chamber between the ends thereof, a gear projecting therefrom, a drive wheel having a gear connection with the motor gear, and oppositely extending oscillating arms operatively connected with said wheel for movement by the latter, said arms having connection respectively with the movable members of the pumps whereby the movable members will be moved in opposite directions at the same time.

6. In an apparatus of the character described, the combination of a vacuum chamber having a plurality of outlet openings in its top, an independent pump for each of

- said outlets mounted upon the top of the vacuum chamber, said pumps comprising relatively fixed and movable parts, and means for independently and detachably supporting each of said pumps upon the top of the vacuum chamber, whereby any one may be bodily removed as a complete unit independently of the others, and means for operating the movable members of the pumps.

7. In an apparatus of the character described, the combination of a vacuum chamber having an outlet opening, a pump supported upon the vacuum chamber comprising oppositely disposed members pivotally connected to one another, and means for supporting one of the members of the pump in fixed position comprising a metallic bracket member secured to one of the members of the pneumatic, said bracket member having an opening establishing communication between the pump and the outlet opening of the vacuum chamber.

8. In an apparatus of the character described, the combination of a vacuum chamber having an outlet opening, a pump supported upon the vacuum chamber comprising oppositely disposed members pivotally connected to one another, means for supporting one of the members of the pump in fixed position comprising a metallic bracket member overlying one surface of one of the members of the pump, said bracket member having an opening establishing communication between the pump and the outlet opening of the vacuum chamber, and means for connecting said bracket member to the wall of the vacuum chamber, whereby the pump is detachably supported upon said vacuum chamber.

9. In an apparatus of the character described, the combination of a vacuum chamber having an outlet opening, a pump supported upon the vacuum chamber comprising oppositely disposed members pivotally connected to one another, and means for supporting one of the members of the pump in fixed position comprising a metallic bracket member overlying one surface of one of the fixed members of the pump, said bracket member having an opening establishing communication between the pump and the outlet opening of the vacuum chamber, a metallic bracket member secured to the movable member of the pump and projecting beyond the end of the fixed member of the pump, and a reciprocating drive rod connected to said metallic member, for imparting swinging movement to the movable member of the pump.

10. In an apparatus of the character described, the combination of a vacuum chamber having an outlet opening in one of the walls thereof, a pump supported on the vacuum chamber and comprising oppositely disposed vertically extending members hingedly connected together at their lower end one of which is fixed and the other movable, the fixed member having an inlet opening and the movable member an outlet opening, and a metallic tube interposed between the vacuum chamber and pump and constituting a closed conduit establishing direct communication between the inlet opening of the fixed member of the pump and the outlet opening of the vacuum chamber, said metallic tube also constituting a supporting medium for said fixed member of the pump, a valve for the outlet opening of the movable member of the pump, and a valve for the outlet opening of the vacuum chamber.

11. In an apparatus of the character described, the combination of a vacuum chamber having an outlet opening in one of the walls thereof, a pump supported on the vacuum chamber and comprising oppositely disposed members one of which is fixed and the other movable, the fixed member having an inlet opening and the movable member an outlet opening, and a closed conduit establishing direct communication between the inlet opening of the fixed member of the pump and the outlet opening of the vacuum chamber, a valve for the outlet opening of the movable member of the pump, and a valve for the outlet opening of the vacuum chamber, said last mentioned valve being positioned within said conduit, and means for detachably supporting the conduit to a wall of the vacuum chamber, whereby the pump may be removed from the vacuum chamber to obtain access to the valve of the outlet in the vacuum chamber.

12. In an apparatus of the character described, the combination of a vacuum chamber having an outlet opening, a pump comprising a relatively fixed and a relatively movable wall, a metallic bracket member positioned upon a wall of the vacuum chamber and constituting a reinforced backing for the fixed member of the pump, said bracket member having an integral tubular extension overlying the opening in the wall of the vacuum chamber and establishing communication therebetween and an opening in the fixed wall of the pump.

13. In an apparatus of the character described, the combination of a vacuum chamber having an outlet opening, a pump comprising a relatively fixed and a relatively movable wall, a metallic bracket member positioned upon a wall of the vacuum chamber and constituting a reinforced backing for the fixed member of the pump, said bracket member having an integral tubular extension overlying the opening in the wall of the vacuum chamber and establishing communication therebetween and an opening in the fixed wall of the pump, and means for imparting movement to the movable member

of the pump including a rod connected to the latter at one end and having operative connection with a drive shaft at its opposite end, and a support for said drive shaft including a member mounted upon the bracket member of the fixed pump section.

14. In an apparatus of the character described, the combination of a vacuum chamber having a plurality of outlet openings at each end thereof, a pump for each opening supported on the vacuum chamber, said pump comprising a fixed and a movable section, the movable section having a supporting part projecting above the adjacent end of the fixed section, a motor mounted upon the vacuum chamber at a point intermediate the pneumatics at the ends of the chamber, a drive wheel operated by the motor and fixedly connected to a drive shaft, and rods having a crank connection with said shaft at one end and a connection with the projecting ends of the movable sections of the pumps at their opposite ends, the parts being constructed and arranged whereby the movable section of the pump at one end of the machine moves in one direction and the movable section of the coöperating pump at the opposite end of the machine will move in an opposite direction, and the movable section of each succeeding pump at one end of the machine will operate in a different direction from that of the adjacent pump at the same end of the machine.

15. In an apparatus of the character described, a vacuum chamber having an outlet in the top adjacent opposite ends, a power actuated drive wheel, a shaft for the wheel, vertically arranged separated pumps adapted to have communication with said outlets, one member of each pump being stationary, and the other movable, an elongated horizontally extending support for said shaft, bridging the space between and supported upon the stationary members of the pumps, and connection between said drive wheel and the movable members of the pumps for operating the latter.

16. In an apparatus of the character described, a vacuum chamber having an outlet in its top adjacent opposite ends, vertically extending pumps adapted to have communication with said outlets, one member of each pump being stationary, and the other hingedly connected thereto so as to be relatively movable, a drive wheel arranged in the space between said pumps, a shaft for said wheel extending transversely of the apparatus, a longitudinally extending support for said shaft extending between and supported upon the stationary members of the pumps, and connection between said drive wheel and the movable members of the pumps for operating the movable members of the respective pumps alternately in opposite directions.

17. In an apparatus of the character de-

scribed, the combination of a vacuum chamber having an outlet opening in one of the walls thereof, a pump supported on the vacuum chamber and comprising oppositely disposed vertically extending pivotally connected members, one of which is fixed and the other movable, the fixed member having intermediate its ends an inlet opening and the movable member having intermediate its ends an outlet opening, and a closed conduit secured at its respective ends to the vacuum chamber and the fixed member of the pump constituting a support for the pump and establishing communication between the outlet opening of the vacuum chamber and the inlet opening of the fixed member of the pump.

18. In an apparatus of the character described, the combination of a vacuum chamber having an outlet opening in one of its walls, a pump mounted on the vacuum chamber and comprising pivotally connected members, and means for removably supporting one of said members of the pump in fixed relation to the vacuum chamber including an elongated bracket member extending over one surface of the pump and detachably secured to the vacuum chamber, said bracket constituting an inlet between the chamber and pump.

19. In an apparatus of the character described, the combination of a vacuum chamber having a plurality of outlet openings in one of its walls, a plurality of pumps mounted on the vacuum chamber one for each opening and comprising pivotally connected members, and means for supporting one of said members of each pump in fixed relation to the vacuum chamber including an elongated bracket member extending over one surface of the pumps and secured to the vacuum chamber, said elongated bracket member constituting a removable support for the pumps whereby they may be independently removed.

20. In an apparatus of the character described, the combination of a vacuum chamber having an outlet opening in its top adjacent one end thereof, a pump mounted on the vacuum chamber and comprising vertically extending pivotally connected members, and means for supporting one of said members of the pump in fixed relation to the vacuum chamber including an elongated bracket member of integral construction extending over the inner surface of the pump and secured to the vacuum chamber, said elongated bracket member having a tubular part establishing a closed communication between the vacuum chamber and the pump.

21. In an apparatus of the character described, the combination of a vacuum chamber having in its top adjacent opposite ends an outlet opening, valves for said openings, pumps supported on the vacuum chamber

and each including oppositely disposed vertically disposed members, one of which is fixed and the other movable, an inlet opening in the fixed member intermediate its ends, and means for removably supporting the pumps upon the vacuum chamber, including bracket members secured to the fixed inner wall of the pumps and removably secured to the vacuum chamber, and operating means for the pumps arranged intermediate the pumps and operatively connected with the movable walls thereof.

22. In an apparatus of the character described, the combination of a vacuum chamber having an outlet opening in one of the walls thereof, a valve for said opening, a pump supported on the vacuum chamber and including oppositely disposed members, one of which is fixed and the other movable, an inlet opening in the fixed member, and means for removably supporting the pump upon the vacuum chamber including a bracket member secured to the fixed surface of the pump and removably secured to the vacuum chamber, said bracket member being of integral metallic construction and overlying the valved opening in the vacuum chamber and providing a closed conduit establishing a communication between said valved opening in the vacuum chamber and the inlet opening of the fixed member of the pump.

23. In an apparatus of the character described, the combination of a vacuum chamber having a plurality of outlet openings at each end thereof, a pump for each opening supported on the vacuum chamber, pumps being reversely arranged at opposite ends of the machine and each comprising a fixed and a movable section, the movable section having a supporting part projecting above the adjacent end of the fixed section, a drive shaft arranged intermediate the ends of the vacuum chamber, a support therefor from the fixed sections, and rods having a crank connection with said shaft at one end and a connection with the projecting ends of the movable sections of the pumps at their opposite ends, the parts being constructed and arranged whereby the movable section of the pump at one end of the machine is collapsed and the movable section of the co-operating pump at the opposite end of the machine is expanded, and the movable section of each succeeding pump at one end of the machine will operate in a different direction from that of the adjacent pump at the same end of the machine.

In testimony whereof I affix my signature in presence of two witnesses.

MORRIS S. WRIGHT.
